TEAKETTLE

Manuel S. Ziskin, University Heights, and Ralph B. Billig, Erieside, Ohio, assignors to Kromex Corporation, Cleveland, Ohio, a corporation of Ohio

Application March 8, 1949, Serial No. 80,166

8 Claims. (Cl. 222—473)

1

This invention relates, as indicated, to a teakettle.

A primary object of the invention is to provide a teakettle which is neat and attractive in appearance, of compact and simple design and construction, and well adapted for normal usage, that is, for the heating or boiling of water for domestic use.

Another object of the invention is to provide a teakettle having a handle of unique and attractive design, a spout closure of unique design, and novel means associated with the handle for raising and lowering the spout closure, such closure-operating means consisting of a minimum number of parts, which are readily accessible to the user of the teakettle.

Another object of the invention is to provide a teakettle comprising a closure operator having a lever which is of such design and is so positioned as to be automatically actuated when the teakettle is lifted from the stove, and is automatically released upon setting of the teakettle on the stove.

A further object of the invention is to provide a teakettle of the character described, the component parts of which are of such simple construction, and are so easy to assemble and disassemble, as to permit of manufacture of the teakettle in commercially desirable quantities, and at relatively low cost.

Other objects and advantages of the invention will be apparent during the course of the following description.

In the accompanying drawings, forming a part of this specification, and in which like numerals are employed to designate like parts throughout the same,

Fig. 1 is a top plan view of a teakettle embodying the invention;

Fig. 2 is a side elevational view of the teakettle, with portions thereof broken away or removed, to show certain details of construction, the spout closure or lid being shown in closed position;

Fig. 3 is a fragmentary cross-sectional view, on an enlarged scale, taken on the line 3—3 of Fig. 1, and with the spout closure in closed position;

Fig. 4 is a view similar to Fig. 3, but showing the spout closure in open position;

Fig. 5 is a fragmentary cross-sectional view, taken on the line 5—5 of Fig. 3;

Fig. 6 is a fragmentary cross-sectional view, taken on the line 6—6 of Fig. 2, and

Fig. 7 is a fragmentary cross-sectional view, taken on the line 7—7 of Fig. 3.

Referring more particularly to the drawings,

2

the teakettle will be seen to comprise a sheet metal shell or receptacle having a cylindrical body portion 1, and a top 2 formed integrally with such body portion and of generally dome-shaped contour. The kettle is provided with a bottom 3, which is telescoped into the body 1, and is rigidly secured to the latter, as by a lock-seam 4, as clearly shown in Fig. 6.

The kettle is also provided with a cylindrical filling and pouring spout 5, which is lock-seamed to the kettle, as at 6 (Fig. 3), to provide a watertight connection with the kettle.

The teakettle is further provided with a handle 7, preferably molded in one piece from a plastic. This handle is shaped or curved to conform with or generally follow the contour of the top of the teakettle, and has a rear foot portion 8 which extends at an inclination to the top of the teakettle, and is secured to the latter by means of a screw 9 and stake nut 10, and a front foot portion 11 which extends vertically to the top of the teakettle and has a curved front surface 12.

The handle is cored out to provide a hollow space 13, which is defined by vertical parallel walls 14 and 15 and an upper wall 16 which is curved longitudinally to conform with the general curvature of the handle, and which terminates at the rear in a socket or recess 17. In its lower portion, adjacent the top of the kettle, the space 13 is bounded at the rear by a surface 18, which serves a purpose to be presently described.

Disposed within the forward portion of the space is a bracket formed of sheet metal, bent to provide a base 19, parallel sides 20 and 21, and a flange 22. The base 19 is curved to conform with the curvature of the top 2 of the teakettle, and is secured to the latter by means of spaced screws 23 extending through the base and through holes in the top 2, and stake nuts 24 secured to the lower ends of the screws and bearing against the inner surface of the top 2. The side 20 of the bracket is in contiguity with the wall 14, and the side 21 is in contiguity with the wall 15. The flange 22 is curved to conform with the curvature of the surface 12 of the handle, and extends vertically to the point 25, the flange, in effect, closing the lower portion of the front opening into the space 13 within the handle.

The teakettle further includes a closure or lid 26, for the spout 5, which closure or lid is preferably molded in one piece from a plastic similar in color to that from which the handle is made. This closure or lid is molded to provide a rib 27

which extends diametrically across the upper surface of the lid from front to rear and has an extension 28 of a width corresponding to the width of the space 13 of the handle, and an extension 29 of a reduced width corresponding to the space between the sides 20 and 21 of the bracket. The closure is pivotally movable about a tubular element 30 which extends transversely through the extension 29 of the lid and is disposed in an opening 31 of said extension. The ends of this tubular element extend beyond the ends of the opening 31 and lie in openings 32 in the walls 20 and 21 of the bracket. The tubular element 30 is of substantially the same length as the space between the walls 14 and 15, and the ends thereof bear against such walls. The tubular element 30 is internally threaded, and is locked in position between the walls 14 and 15 by means of short screws 33 which extend through openings 34 in the handle and into the ends of the tubular element 30, and the heads of which lie in counterbores 35 of the openings 34. This manner of mounting the tubular pin 30 enables the tubular element to also act as a spacer to prevent collapse of the walls 14 and 15, which collapse would squeeze the sides 20 and 21 of the bracket against the sides of the extension 29, and thereby prevent easy pivotal movement of the lid about the pin. The closure or lid 26 thus normally rests on the upper edge of the spout 5, with the extension 29 thereof extending into the space between the sides 20 and 21 of the bracket, and pivotally secured to the bracket by means of the pivot pin 30. The screws 33 and pivot pin 30 thus serve not only as a means of securing the closure or lid to the bracket, but also as a means of securing the handle against displacement from the top 2 of the teakettle.

The closure or lid 26 has a central opening 36 which communicates with an air space 37 within the closure, and is in axial alignment with the central opening 38 of a metallic disc 39, which is secured to the closure below the space 37 by means of a rivet 40. This combination of elements forms a whistle which is actuated in response to steam pressure within the teakettle to indicate that the water therein has attained the proper temperature.

The teakettle further includes a closure operator in the form of a lever or trigger 41, preferably formed of a plastic of a color different from that of the handle and lid, of a width corresponding to the width of the space 13 in the handle. The lever 41 is disposed below the handle and extends substantially from the rear foot portion 8 to the front foot portion 11 of the handle, being provided at its rear end with a cylindrical extension 42 which is seated in the socket or recess 17, and with a downturned forward portion or toe 43, provided in its front face with a recess 44. The lever 41 is thus pivotally movable in a vertical plane, about the pivot point or axis indicated at 45.

The closure operator further includes a toggle member formed of wire which is bent to provide an intermediate coiled portion 46, a forward extension or toe 47 and a rearward extension or heel 48. The coiled portion 46 of the toggle member is pivotally movable about a pivot pin 49, which extends between the sides 20 and 21 of the bracket, and has its ends mounted in holes 50 in said sides, the pin being substantially equivalent in length to the width of the space between the walls 14 and 15 of the handle, so as to be

retained by said walls against axial displacement from the bracket. The toe 47 of the toggle member rests on the extension 29 of the lid 26, and the heel 48 extends into the recess 44 of the lever 41, resting on the ledge 51 which forms the bottom of said recess. The coiled portion 46 of the toggle member is tensioned sufficiently to cause the toe 47 and heel 48 to bear with slight resiliency on the parts on which they rest.

The lever 41 is normally maintained in the position shown in Figs. 1, 2 and 3, by means of a U-shaped compression spring 52, which is disposed below the extension 29 of the lid 26, one arm 53 of this spring bearing against the lower surface of the extension 29, and the other arm 54 of the spring bearing against the heads of the screws 23. Longitudinal displacement of the spring 52 is prevented by virtue of the engagement of the bight of the spring with the flange 55 of the bracket, and the engagement of a flange 55 on the arm 54 with the surface 18 of the handle.

It will also be noted that the upper end of the surface 18 forms a stop for the toe 43 of the lever 41, so that the lever cannot descend below the position shown in Fig. 3. Moreover, the lower end of the front face of the toe 43, at all times, engages or substantially engages, the rear edges of the sides 20 and 21 of the bracket, so that the lever cannot be longitudinally displaced from the socket 17 of the handle.

The teakettle, as thus described, is neat and attractive in appearance, is extremely compact and simple in design and construction, and is admirably adapted for normal usage, that is, for the heating or boiling of water for various purposes.

It may be filled with water to the desired depth, the water being introduced through the spout and also dispensed therethrough after being heated. As the teakettle is lifted from the stove, preparatory to dispensing the water from the spout, it is grasped by the handle 7, the fingers of the hand will virtually automatically squeeze the lever 41, causing it to pivot about the axis 45 and moving it upwardly into the space 13 of the handle. This causes the toggle member to rock about the pivot pin 49, which, in turn, causes the closure or lid 26 to be opened. In this manner, the lid is opened virtually simultaneously with the lifting of the teakettle from the stove, and the contents of the teakettle may be poured by merely tilting the teakettle. This is in contrast to existing teakettles, in which the opening of the lid is accomplished as a second and separate step, from the lifting of the teakettle from the stove.

During the aforesaid operation, the spring 52 is compressed so that when the teakettle is again set down on the stove, the conjoint weight of the closure and lever and action of the spring serve to bring the closure to its closed position. This action is also virtually a single operation, since the lever is released simultaneously with the setting down of the teakettle.

Due to the slight resiliency of the parts 41 and 38 of the toggle member, these parts will always remain in contact with the parts on which they bear, irrespective of slight wear of various portions of these parts, or inaccuracies of fitting due to large tolerances, so that the teakettle will, at all times, remain in usable and operable condition.

It will be apparent that the handle is of unique and attractive design, that the spout closure is of unique design, and that the closure operating means consists of a minimum number of parts

which are readily accessible to the user of the teakettle, and that the component parts are of simple construction, and are so easy to assemble and disassemble, as to permit of manufacture of the teakettle in commercially desirable quantities, and at relatively low cost.

It is to be understood that the form of our invention, herewith shown and described, is to be taken as a preferred example of the same, and that various changes in the shape, size and arrangement of parts may be resorted to, without departing from the spirit of our invention, or the scope of the subjoined claims.

Having thus described our invention, we claim:

1. A teakettle comprising a receptacle having a cylindrical body portion and a closed top formed integrally with said body portion, a spout extending from said receptacle, a closure for said spout, a handle having a rear foot portion secured to said receptacle and a front foot portion in contiguity with said receptacle, said handle having a recess in said front foot portion, said recess having transversely spaced parallel vertical wall surfaces, a sheet metal bracket disposed in said recess, said bracket having a base and parallel vertical walls in contiguity with the walls of said recess, means securing said base to said receptacle, said spout closure having a rearward extension disposed between said bracket walls, and means for pivotally securing said extension to said bracket, said last-named means comprising a hollow pin extending through said extension and having the ends thereof mounted in the walls of said bracket, said pin restrained against axial movement by the walls of said recess, and screws extending through said handle and in threaded engagement with the ends of said pin.

2. A teakettle, as defined in claim 1, in which said recess extends into the lower portion of said handle and to a point adjacent the upper end of the rear foot portion of the handle, forming a slot, and a lever is pivotally mounted in said slot, said lever extending substantially the full length of said slot and normally projecting beyond the lower edge of the slot, said lever adapted to be elevated by the fingers of the hand which grasps said handle, said closure being elevatable upon elevation of said lever.

3. A teakettle, as defined in claim 2, in which a toggle member is provided which is mounted for rocking movement about a pin on said bracket, said toggle member having a toe portion re-

silently bearing on said closure extension, and a heel portion resiliently bearing on said lever.

4. A teakettle, as defined in claim 3, in which said last-named pin has its ends mounted in the walls of said bracket and is restrained against axial movement by the walls of said recess.

5. A teakettle, as defined in claim 4, in which said lever is pivotally mounted in the handle at a point adjacent the upper end of the rear foot portion of the handle, and is restrained against longitudinal displacement from the handle by said bracket.

6. In a teakettle of the character described, a receptacle having a cylindrical body portion and a closed top formed integrally with said body portion, a spout extending from said receptacle, a closure for said spout, a handle secured to the closed top of said receptacle and having the major portion thereof extending in a substantially horizontal plane across said closed top, and means for raising said closure, said means comprising a substantially horizontal lever mounted in the lower portion of said horizontal portion of said handle and extending substantially the entire length of said horizontal portion of the handle and partially concealed within the handle, and adapted to be elevated by the fingers of the hand, simultaneously with the grasping of the handle when the teakettle is lifted.

7. A teakettle, as defined in claim 6, in which said lever is mounted at its rear end for pivotal movement in the plane of the handle.

8. A teakettle, as defined in claim 6, including means for retaining said lever against displacement longitudinally of the handle.
